UNITED STATES PATENT OFFICE.

ANDREW J. SANFORD, OF NEWARK, OHIO, ASSIGNOR TO A. H. HEISEY & CO. INC., OF NEWARK, OHIO, A CORPORATION OF WEST VIRGINIA.

DESIGN FOR A SALT-SHAKER.

42,441.

Specification for Design.

Patented Apr. 30, 1912.

Application filed January 18, 1912. Serial No. 672,001. Term of patent 14 years.

To all whom it may concern:

Be it known that I, ANDREW J. SANFORD, a citizen of the United States, residing at Newark, county of Licking, State of Ohio, have invented a new, original, and ornamental Design for Salt-Shakers, of which the following is a specification, reference being had to the accompanying drawing, forming part thereof.

The figure is a perspective view of a salt shaker showing my new design.

I claim:

The ornamental design for a salt shaker, as shown.

ANDREW J. SANFORD.

Witnesses:

I. M. PHILLIPS,
FREDERIC C. HALL.
